UNITED STATES PATENT OFFICE.

JOHN C. SCHLITTEHARDT, OF NEWARK, AND JULIUS E. DORNING, OF VAILSBURG, NEW JERSEY.

GAS-COCK.

SPECIFICATION forming part of Letters Patent No. 762,001, dated June 7, 1904.

Application filed March 15, 1904. Serial No. 198,311. (No model.)

To all whom it may concern:

Be it known that we, JOHN C. SCHLITTEHARDT, residing at Newark, and JULIUS E. DORNING, residing at Vailsburg, in the county 5 of Essex and State of New Jersey, citizens of the United States, have invented certain new and useful Improvements in Gas-Cocks; and we do hereby declare the following to be a full, clear, and exact description of the invention, 10 such as will enable others skilled in the art to which it appertains to make and use the same, reference being had to the accompanying drawings, and to numerals of reference marked thereon, which form a part of this specification. 15

The objects of this invention are to prevent the accidental opening of the gas-cock, whereby the gas is permitted to escape into the room and injuriously affect the occupant; to 20 secure a device of greater neatness of appearance when applied to the burner; to reduce the cost of construction, and to obtain other advantages and results, some of which may be referred to in connection with the description 25 of the working parts.

The invention consists in the improved safety attachment for gas-cocks and in the arrangements and combinations of parts of the same, all substantially as will be hereinafter 30 set forth and finally embraced in the clauses of the claim.

Referring to the accompanying drawings, in which like numerals of reference indicate corresponding parts in each of the several figures, Figure 1 is a side elevation of a portion 35 of a gas-cock having our improvements attached. Fig. 2 is a bottom plan of the same, and Fig. 3 is a front view of the safety device detached from the cock.

In said drawings, 10 indicates the body of the cock.

11 indicates the valve plug or key, by means of which the passage for the gas through the cock is opened and closed, the said valve plug 45 or key having a reduced round part 12 and a flat finger portion 13, by means of which last the said plug or key is easily turned by the thumb and finger.

The safety device comprises a sheet-metal 50 piece which is doubled or U-shaped at its

lower part, being bent, as at 14, to form an upper and a lower extension. At the extremity of the upper extension 16 the said sheet-metal piece is bifurcated, as shown in Fig. 3, the arms 17 17 being twisted and bent so as 55 to extend oppositely around the body of the cock and being fastened together by a bolt, rivet, or the like 18 at the extremities. The arms being fastened around said body, as above detailed, the extension 16 projects from 60 said arms in a direction parallel with the body of the cock away from the plug or key and at some little distance from said plug or key has the bend or curvature 14, where the upper extension connects with the lower ex- 65 tension 15. Said lower extension is longer than the upper and projects across the longitudinal axial line of the said plug or key, in which line it is transversely slotted, as indicated in Fig. 2, the extension being made 70 wider at said slot to enable the said slot to be properly made. Said extension 15 when attached to the cock lies normally in the central horizontal plane of the flat finger portion, as shown in Fig. 2, the said finger portion 75 lying transversely in the slot 20, thus being locked or prevented from turning to its open position, (shown in the broken outline.)

To open the key or plug, the operator grasps the flat portion 13 and in doing so 80 raises the extension 15, so that the central enlargement 20 of the slot receives the reduced shank or part 12 of the key, the flat part clearing the narrow portions of said slot, as will be understood. Thus the key or plug may 85 be turned to its open position.

On closing off the gas by turning the flat portion to its transverse or closing position the resilient extension 15 assumes its normal position with considerable energy, producing 90 a clicking noise by which the operator will receive an audible signal of its locking, and said spring will strike the fingers, so that the signal will be emphasized by the sense of touch. Being locked automatically, there is 95 no danger of accidental or inadvertent opening of the valve, as will be obvious.

Having thus described the invention, what we claim as new is—

1. The improved safety attachment for 100

ocks, comprising a sheet-metal piece bifurcated at one end, and made U-shaped at the other, one of the extensions of the U-shaped part having a transverse slot and means for 5 fastening the attachment to the body of the cock.

2. The improved safety attachment for gas-
ocks, comprising a resilient piece of metal
having the arms 17, extension 16, at an angle
10 to said arms, the curvilinear bend 14, and
longer extension 15, adapted to cross the axial
line of the plug or key and having a trans-
verse slot, the center of which is enlarged,
and means for joining the extremities of said
15 arms, substantially as set forth.
3. The improved safety attachment for gas-

ocks, comprising a resilient piece of metal
having the arms 17, extension 16, at an angle
to said arms, the curvilinear bend 14, and
longer extension 15, adapted to cross the axial 20
line of the plug or key and having a trans-
verse slot, and means for joining the extremi-
ties of said arms, substantially as set forth.

In testimony that we claim the foregoing we
have hereunto set our hands this 12th day of 25
March, 1904.

JOHN C. SCHLITTENHARDT.
JULIUS E. DORNIG.
